Chef Pierre, Inc., Traverse City, Mich.

Filed Oct. 15, 1970, Ser. No. 25,510

Term of patent 14 years

Int. Cl. D9—03

U.S. Cl. D9—193

FIG. 1

FIG. 2

FIG. 3

FIG. 1 is a side elevational view of a packaged pie showing my new design, the side opposite being substantially the same;

FIG. 2 is a fragmentary sectional view thereof taken on line 2—2 of FIG. 1; and

FIG. 3 is a sectional view thereof taken on line 3—3 of FIG. 1 on a reduced scale.

My design for a packaged pie is characterized by the rim of the container and the edge crust of the pie overhanging the supporting ring, and the transparent wrapper covering the heaped, top portion flowing over the top of the pie and over the edge crust where it curves inwardly adjacent the support ring following its surface to the underside of the pie where it curves upwardly toward the bottom of the container.

I claim:

The ornamental design for a packaged pie, substantially as shown and described.
